UNITED STATES PATENT OFFICE.

DAVID P. CLARK AND CHARLES F. BLACK, OF DAYTON, OHIO; SAID BLACK ASSIGNOR
TO SAID CLARK.

TOY.

1,128,291.

Specification of Letters Patent. Patented Feb. 16, 1915.

Application filed March 11, 1914. Serial No. 823,850.

To all whom it may concern:

Be it known that we, DAVID P. CLARK and CHARLES F. BLACK, citizens of the United States, residing at Dayton, in the county of 5 Montgomery and State of Ohio, have invented certain new and useful Improvements in Toys, of which the following is a specification, reference being had therein to the accompanying drawing.

10 This invention relates to toys and more particularly to toy structures which are built up from separate sections and which are of such a character that they may be provided with a movable motor driven car 15 of some kind.

The object of the invention is to provide a structure which can be built up from separate parts by a child and which will have a passageway for a car and will have connected therewith a motor by means of which the car may be operated, and will also have means by which the movement of the car may be controlled by the child or other operator.

20 A further object of the invention is to provide a structure which can be readily converted from one form to another and to this end it is also an object of the invention to provide a special joint for connecting together the separate sections or structural members of which the structure as a whole is built up and for rigidly retaining these parts in their proper relative positions; and further, to so construct the joint that it can 30 be readily detached from the members when it is desired to take the device apart or to change its form.

In the accompanying drawings, Figure 1 is a side elevation of a toy structure built in 40 imitation of a tower and embodying our invention; Fig. 2 is an end elevation of the shafting and controlling devices mounted at the top of the tower; Fig. 3 is a plan view of the same, with the shafting broken away at 45 one end; Fig. 4 is a detail view of the connecting joint; Fig. 5 is a detail view of one of the fastening devices; Fig. 6 is a horizontal, sectional view taken through one of the joints and portions of two horizontal bars showing two forms of fastening de-

vice; Fig. 7 is a sectional view taken on the line α α of Fig. 1, looking in the direction of the arrows and showing the motor in section; Fig. 8 is a side elevation of the structure changed to imitate a bridge; and Fig. 9 is a transverse, sectional view of the bridge structure.

In these drawings we have illustrated one embodiment of the invention and have shown the same as comprising a built-up 60 structure which, while primarily designed to be constructed in imitation of either a tower or a bridge, is susceptible of being modified in various ways and may be made imitative of other devices. The tower 65 structure, as here shown, comprises a series of upright or longitudinal members, each of which is made up of a series of sections 1, which sections, in the present embodiment of the invention, are in the form of bars of 70 angle iron. The several sections of each longitudinal member are connected one to the other in such a manner that they can be readily disconnected and the arrangement of the parts varied. In the present in- 75 stance, we have shown the sections as connected one to the other by means of a joint 2 which comprises a plate bent at an angle, adapted to fit snugly against the outside of the angle bars and having its edges bent in- 80 ward, as shown at 3, to form guideways to receive the ends of the angle bars and retain the same against lateral displacement. The several upright members are connected one to the other by means of transverse 85 members or cross bars 4 which may be connected either directly to the angle bars or to the joints 2, by means of which the angle bars are connected one to the other. In the present construction of the tower we have 90 shown cross bars extending not only be- 95 tween the several joints but also connected with the angle bars between the joints. The manner of connecting the cross bars with the joints is similar to that by means of which the joints are connected with the angle bars. The angular plates comprising the joints are provided with laterally ex- 100 tends portions 5 having their ends turned inward, as shown at 6, to receive the ad-

jacent ends of the respective cross bars and retain the same against lateral displacement.

Any suitable means may be provided for retaining the cross bars against lengthwise movement and for preventing the movement of the angle bars or joints relatively to the cross bars. Preferably both the cross bars and the joints, or the angle bars, with which they are to be connected, are provided with 10 openings 7 adapted to receive suitable fastening devices. A very simple form of fastening device is shown at 8 in Fig. 6 and comprises a head having two substantially parallel legs bowed outwardly in opposite 15 directions at points slightly removed from the head and having their outer ends arranged close together to facilitate the entrance of the same into the openings. When one of these fastening devices is forced 20 through the openings in cross bar and the part to which it is to be connected the bowed portions of the lugs will be forced inward until they have cleared the edges of the openings, when they will spring outward 25 and thus retain the fastener against displacement until force is applied thereto. There is very little tendency on the part of the cross bars to move laterally relatively to the joints or the angle bars and, consequently, there is little or no strain longitudinally of the fastening device. We have 30 also shown a second form of fastening device which is adapted for use in the same position as the fastening device 8 but which is particularly desirable where longitudinal strain may be imposed upon the fastening device. This second form of fastening device is shown at 9 in Figs. 5 and 6 and comprises a shank having a head and a T-shaped 35 foot adapted to extend through an oblong opening and to be turned through a quarter of a revolution to lock the same against withdrawal. This, of course, requires the use of oblong openings in at least one of the 40 bars or joints which are to be connected and while it is applicable to make any of the connections in the structure we have shown it in the drawings as used for connecting brackets 10, which receive the lower ends 45 of the upright members, to a base 11 on which the tower as a whole is mounted. The tower as at present constructed is rectangular in cross section and there are four upright members all tied together by the 50 cross bars 4, but it will be understood that the number of upright members may be varied and the tower thus given different cross sectional shapes.

The space within the tower forms a passage in which a car 12 may be moved after the manner of an elevator car. The car, as here shown, is not mounted in tracks of any kind but has apertured lugs 13 forming guideways to receive cords or cables extend-

ing from the top to the bottom of the tower 61 to guide the car in its movement. Movement is preferably imparted to the car by means of a motor which is here shown at 15 as an inertia motor but it will be understood that other kinds of motors may be used if 71 desired, although this particular motor is very efficient. The motor here shown does not form a part of the present invention but is similar to that shown and described in Patent No. 1,054,339, granted to David P. 7 Clark February 27th, 1913. This motor comprises an inertia wheel 16 mounted on a shaft 17 having pinions 18 on opposite sides of the inertia wheel, and the inertia wheel and the shaft are capable of bodily movement to move the pinions into operative relation either with gearing 19 connected with a crank 20 or with gearing 21 connected with a pulley 22. Bodily movement may be imparted to the inertia wheel by means of a 8 lever 24 projecting beyond the casing which incloses the mechanism thereof. Mounted at the top of the tower and preferably journaled in the uppermost cross bars 4 are two shafts 25 having secured thereto pulleys 26 9 about which extend endless belts or cables 27, which belts or cables also extend about the pulley of the motor. The shafts 25 also have secured thereto pinions 28 and the cables are so arranged that the pinions will 9 be rotated in the same direction. A third shaft 29 is rotatably mounted in the upper cross bars 4 between the shafts 25 and has one end mounted for lateral sliding movement as well as rotary movement. The 1 shaft 29 has a gear 30 arranged to be moved into mesh with either of the pinions 28 or to be moved into a neutral position, free from both gears. A portion of this shaft 29 forms a drum about which is wound a cable 1 31, the free end of which is connected with the car 12. Inasmuch as the pinions 28 rotate in the same direction it is obvious that when the gear is in mesh with one of these pinions the cable 31 will be wound about the 1 drum or shaft and when the gear is in mesh with the other pinion the cable will be unwound therefrom. The shifting of the gear into and out of mesh with the pinions is controlled by the end of the shaft which projects beyond the cross bar on which it is mounted and forms a handle, as indicated at 32.

It will be apparent from the foregoing description that in the operation of the device the inertia wheel is first connected with the crank 20, which crank is operated to impart to the inertia wheel the desired movement, after which the inertia wheel is shifted to connect it with the pulleys and these pulleys are thereby set in operation, causing the cable to be wound or unwound from the shaft or drum 29. As the car approaches the

limit of its movement in one direction the shaft is shifted to reverse the movement of the drum and cause the car to move in the opposite direction. By thus reversing the 5 movement of the car as it approaches the upper or lower limits of its movement it can be kept in motion until the power of the motor has been exhausted.

In Fig. 8 of the drawings we have shown 10 the structure as arranged in a horizontal position and modified to give it the appearance of a bridge. To this end the lower sections of the upright members are separated from those portions thereof which 15 are placed in horizontal position, and are allowed to remain in vertical positions upon the base 11 where they form abutments 33 for the adjacent end of the horizontal structure, the lower longitudinal members of 20 which are connected with the abutment forming members by a modified form of the joint 2, as shown at 34, this modified form of the joint having a downwardly extending arm to receive the upper ends of the 25 upwardly extending abutment members. Other sections of the angle bars are attached in a similar manner to the opposite end of the horizontal structure to form abutments 33 for that end and, if desired, these abutments 30 may be mounted upon a base 35. In the bridge structure we also prefer to employ diagonal truss bars 36, which are secured to the main structure by removable fastening devices such for example as those 35 shown at 8 and 9, removing one or more sections of the longitudinal members at the top of the horizontal structure and at each end thereof and also the cross bars 4 which are connected to the removed sections, the top of 40 the structure is reduced to a less length than the bottom and the ends of the side walls thereof are inclined after the manner of a bridge. Suitable tracks 43 are mounted upon the cross bars 4 extending between the 45 two lower longitudinal members and mounted upon each track is a car 37 connected one to the other by means of a cable 38 which passes about a pulley or guide 39 and each connected at its front end by cables 40 with 50 the pulleys 26 of the shafts 25. The controlling mechanism for the car, including these shafts, is preferably mounted upon the abutment, 33, at one end of the bridge, this being accomplished by removing the cross 55 bars 4 which carry this controlling mechanism from the top of the tower and placing the same in position at the top of the abutment sections 33. A single endless belt 41 connects the pulley 22 of the motor with the 60 drum of the shaft 29. Thus, it will be noted that the operation of the controlling members is just reversed, the power being applied to the shaft 29 and distributed to the two cars by the pulleys 26 according to the

position of the gear 30 relatively to the pin- 65 ion 28.

While we have shown and described one embodiment of our invention it will be understood that this has been chosen for the purposes of illustration only and that we do 70 not desire to be limited to the details of construction shown and described, for obvious modifications will occur to a person skilled in the art.

Having thus fully described our invention, what we claim as new and desire to secure by Letters Patent, is:—

1. A toy structure imitative of a tower when placed vertically and imitative of a bridge when placed horizontally, some parts 80 thereof being removable to vary the design somewhat when in one position and the other, means to cause a car to travel vertically when the toy is in tower-position and horizontally when in bridge-position, a motor, and operating devices driven thereby and adapted to move the car back and forth in the structure.

2. The combination, with a toy structure having a passageway, of a motor adapted to 90 produce rotary motion for a limited period of time, a car arranged to travel back and forth in said passageway, and devices connecting the motor and car characterized by 95 the quality of converting the rotary motion of the motor into reciprocatory motion for the car.

3. A toy structure comprising a series of longitudinal members connected one to the other to form a passageway between them, a 100 car mounted to travel in said passageway, a motor mounted at one end of said passageway, a rotary drum, two pulleys connected respectively with the car and the motor, pinions connected with said pulleys, and a 105 gear connected with said drum and movable into mesh with either of said pinions, whereby said car may be caused to move alternately in opposite directions.

4. A toy structure comprising a plurality 110 of longitudinal members, each member comprising a series of sections separately connected one to the other, cross members detachably connected with said longitudinal members to connect the latter one to the 115 other, whereby a portion of the longitudinal members on one side of said structure may be removed and placed beneath the other side thereof when the structure is in horizontal position to form supports therefor, a 120 motor arranged at one end of said structure, a car mounted to move lengthwise thereof, cables connecting said motor with said car, and a controlling device for causing said car to move alternately in opposite directions. 125

5. In a toy structure, a plurality of vertical members connected one with the other by cross members to form a tower, a motor

1 mounted at the base of said tower, and having a pulley, three shafts arranged side by side and supported at the upper end of said tower, the two outside shafts having pulleys, cables connecting said pulleys respectively with the pulley on said motor, an intermediate shaft comprising a drum, a cable wound about said drum, a car connected with said cable and arranged to travel vertically in said tower, pinions secured to the outside shafts, and a gear secured to the intermediate shaft, said latter shaft being ca-

pable of bodily movement to cause said gear to mesh with either of said pinions.

In testimony whereof, we affix our signatures in presence of two witnesses.
